REFRIGERATION APPARATUS

Kemper Martel Hammell, Minster, Ohio

Application October 16, 1931, Serial No. 569,248

12 Claims. (Cl. 62—115)

Another object of my invention is to provide a refrigeration apparatus that eliminates the use of reducing or expansion valves.

Another object of my invention is to provide a refrigeration apparatus that will allow the motor to start under a very light load and gradually build up its load without the use of valves or other complicated mechanism generally used to allow the motor to attain normal speed before the load is applied.

Another object of my invention is to provide an apparatus that reduces vibration and noise.

Another object of my invention is to provide a refrigeration apparatus that is compact, and at the same time efficient.

With these and other objects in view, my invention consists in the arrangements, construction, and combination of the various parts of my improved device as described in the specification, claimed in the claims and illustrated in the accompanying drawings.

In the drawings:

Fig. 1 is a side elevation, partially in section, of a refrigeration apparatus, embodying my improvements in a simple form.

Fig. 2 is a sectional view taken on the line 2—2 of Fig. 1 showing one type of sealing means that may be used in this type of refrigeration apparatus.

Fig. 3 is an enlarged sectional view taken along the line 3—3 of Fig. 1 showing a means for connecting the motor to the system.

Fig. 4 is a sectional view, taken along the line 4—4, of Fig. 1, showing the blades or vanes in the compressor and the fins in the condenser.

Fig. 5 is a top view of the blade used to keep the gas or vapor from whirling in the passageway leading to the compressor.

Fig. 6 embodies another improvement in my invention.

Fig. 7 is a diagrammatic sketch of another type of compressor that may be used in my invention.

In the drawings I have shown at 13, a portion of a refrigeration box which may be of any suitable construction, within which is placed the vaporizer or cooling element 11. The remainder of the refrigeration apparatus may be placed in a separate compartment which is integral with the refrigeration box or insulated cabinet 13, or it may be placed on the outside of the same. In the drawings I have shown this mechanism arranged on the top of the box. It comprises a frame 14, supporting an electric motor 12, and the rotating compressor and condenser 10, being connected therewith. The electric motor 12, is not

clamped directly to the frame 14. A rubber, fibrous, or any suitable vibration absorbing material 16 is fastened to the motor flange 15. This vibration absorbing material 16 is in turn fastened to the frame 14 by means of the bolts 17 although any other suitable method of fastening the vibration absorbing material may be used. To the motor shaft 19 is fastened a hub with a flanged portion 18. Fig. 3 shows one method of fastening this flanged member to the motor shaft so the motor may be removed without breaking the seal or disturbing the remainder of the system. The flanged member 18 is fastened to the drum 10 so there is a direct connection between the motor shaft 19 and the drum 10. The drum 10 is composed of a compressor and condenser. Figs. 1 and 4 show the compressor composed of helical blades 21. When the drum rotates, these blades act as a centrifugal pump, compressing the vapor and discharging the compressed vapor into the outer portion of the drum 10 which is the condenser.

Fig. 7 is a diagrammatic sketch of a piston pump that may be used for a compressor. If this type of compressor is used, the crank shaft 42 is stationary and the piston 43 rotates with the drum 10. When the piston is on the suction stroke, the valve 41 will be open and vapor from the passageway 22 will enter the cylinder. During this time, the valve 40 is closed. On the compression stroke, valve 41 is closed, the vapor is compressed, and the valve 40 opens and discharges the compressed vapor in the outer portion of the drum 10 which is the condenser. The outer portion of the drum is separated from the inner portion by means of a wall 44. In this wall or partition is placed a valve 45 and valve seat 46. This valve has appreciable weight and is held on the seat during the rotation of drum 10 by means of centrifugal force. As soon as the drum 10 stops, valve 45 opens and the condensed refrigerant flows back to passage 22 and into the vaporizer 11. If a centrifugal pump is used, any type of blades may be used or any other type of a pump such as a gear pump or rotary pump may be used for a compressor.

In the outer portion of the drum 10 are located a number of fins 23. This portion of the drum is the condenser. These fins are fastened alternately to the upper and lower side of the drum 10 so that the compressed vapor will be deflected against the walls of the drum as it passes toward the periphery of the drum 10. The vapor heated during compression is, by said arrangement of fins 23, passed over a large area of metal which

absorbs the heat and conducts it to the outer surface of the drum where the heat is absorbed by the air coming in contact with the surface of said drum. The vapor condenses in the outer portion of said drum and passes through the tube 24 to the passageway 22 and then into the vaporizer 11. The openings 25 are also passageways for the condensed refrigerant to flow to compressor and then follow the spiral path of the pump 5 blades 21 into the passageway 22 and back to the vaporizer 11. The tube 27 is fastened to the drum 10 and extends into the tube 29 forming the passageway 22 which connects the compressor and vaporizer. In order to seal the space between 10 the rotating tube 27 and the stationary tube 29, an annular cup 26 is fastened to last said tube and is partially filled with a non-volatile liquid, a conical shaped member 28 is fastened to the tube 27 and dips into the liquid in the annular cup 26 as shown in Fig. 1. Thus a sealed passageway is formed between the compressor and the vaporizer. Other suitable types of seals may be used for sealing the refrigeration system.

The vaporizer 11 is a metal container which 25 may or may not have external radiator fins and internal baffle plate to guide the convection currents of the refrigerant. The vaporizer 11 is held in position by brackets 31 which are fastened to the refrigerator box 13. The vaporizer 11 may 30 have pockets for drawers 32 for freezing water and desserts. The refrigerator box 13 has an opening through which tube 29 extends and the remainder of which is filled with a suitable packing material 30. Said opening allows the annular cup 35 26 to readily pass through the refrigerator box 13 when the cooling element or vaporizer is placed into or taken out of position.

A baffle 33 shown in Figs. 1, 2, 4, and 5 prevents the vapor from rotating while it passes 40 through the rotating tube 27 and into the pump inlet. This baffle 33 may be of any shape that prevents this rotation.

A thermostatic motor switch is placed near the outer surface of the cooling element 11 and 45 is controlled by means of a knob 34. This knob so controls the thermostat that a desired substantially constant temperature is maintained in the refrigerator box.

The motor and rotating drum are enclosed 50 in the inverted can or case 35 which is lined with a sound absorbing material 36. The sound absorbing material tends to absorb any noise made by the motor 12, the rotating drum 10 or the fins 38.

The opening 37 is to allow air circulation 55 about drum 11 for cooling.

The fins 38 in Fig. 6 are fastened to the outer side of drum 10 to aid circulation of air about the drum. Any type of fins that agitate the 60 air sufficiently may be used.

When the machine first is set up or the seal 65 broken, the air must be expelled from the apparatus. To do this, the machine is assembled with the proper amount of refrigerant in the vaporizer 11. The motor 12 is then turned on, thus causing the drum 10 to rotate. The action of the pump tends to produce a vacuum in the vaporizer 11, causing the refrigerant to evaporate and displace the air in the drum 10. During this time, the plug 39 is not in position so 70 that the air is expelled through the opening from which plug 39 was removed. As soon as the air has been expelled, the plug 39 is inserted, thus sealing the apparatus. The apparatus is then 75 ready for operation.

When the machine is to be operated, the motor must be connected to the proper electric circuit. Due to the temperature, the thermostatic switch will be closed so the armature of the motor will begin to rotate and cause the drum 10 to rotate. Vaporized refrigerant is drawn into the pump from passage 22 and is discharged into the outer portion of the drum which is the condenser. The compressed vapor is hurled against the internal radiator fins 23 by centrifugal force. Compressing and removing the heat from the vaporized refrigerant causes it to condense. The condensed refrigerant collects around the periphery of the drum 10.

While the pump is in operation, a partial vacuum is produced in passage 22 and in the vaporizer 11. The reduced pressure causes the refrigerant in the vaporizer 11 to vaporize more rapidly. The evaporation process absorbs heat and thus cools the remaining refrigerant and the vaporizer. This action continues until the temperature about the thermostat reaches a predetermined point. At that time the thermostat switch is automatically opened and the motor ceases to cause the drum to rotate.

During rotation, liquid refrigerant is continuously returned to the vaporizer 11 through the tube 24. Means for preventing vapor from returning through tube 24 may be used. Upon ceasing of rotation, the remainder of the liquid refrigerant in the condenser flows to the pump through passages 25, through the passage between vanes of said pump, then down the passage 22 into the vaporizer 11.

As soon as the temperature about the thermostat rises to a predetermined point, the thermostat automatically closes the motor switch thus causing the motor to rotate the drum 10 and the cycle is repeated.

The knob 34 is used to regulate the thermostat 40 so that any desired temperature can be maintained within the refrigerator box.

There are several refrigerants that can be used in my refrigeration apparatus such as carbon disulphide or carbon tetrachloride. The refrigerant should have a comparatively large molecular weight so that the vapor given off is heavy, as a heavy gas can be condensed more readily in my type of apparatus.

While I have described several embodiments of 50 my invention, I do not wish to be limited to the particular forms shown and described as it will be apparent that many modifications therein may be made without departing from the scope of my invention as set forth in the appended claims.

Having thus described my invention, what I claim is:

1. In a refrigeration system, a rotating condenser, a compressor within said condenser, and a stationary vaporizer or cooling unit.

2. In a refrigeration system, a stationary vaporizer and a unit comprising a compressor and condenser, said unit being rotated by a means of a motor and having communication with said stationary vaporizer or cooling element.

3. In a refrigeration system, a motor driven drum; said drum comprising a reciprocating pump and condenser, said drum communicating with a stationary cooling unit or vaporizer, said condenser having a baffled vapor passageway.

4. In a refrigeration system, a rotating unit, comprising a compressor and a condenser and a stationary unit comprising a vaporizer.

5. In a refrigerator comprising an insulated cabinet, a compressor outside of said insulated

- 5 cabinet, motor for rotating said compressor, said compressor having a passageway leading into said insulated cabinet and communicating with a vaporizer, a portion of said passageway being comprised of a rotating cylinder, means extending axially into said rotating cylinder to keep the gas from rotating within said rotating cylinder.
- 10 6. In a refrigeration system, the combination of a stationary vaporizer and a motor directly connected to a drum, said drum comprising a compressor and condenser, said drum having a passage for feeding vapor to said compressor and a passage for returning condensate to said stationary vaporizer or cooling element.
- 15 7. In a refrigerator comprising an insulated cabinet, a drum outside of said insulated cabinet, motor for rotating said drum, said drum having a passageway leading into said insulated cabinet and communicating with a stationary vaporizer within said insulated cabinet, a thermostatic element within said insulated cabinet controlling the operation of said motor in order to maintain a substantially constant selective temperature within said insulated cabinet.
- 20 8. In a refrigeration system, a drum, means for rotating said drum, said drum having a compressor near its center and having fins spaced between said compressor and the periphery of said drum, a passageway connecting said drum to a vaporizer or cooling element, a portion of said passageway being composed of a rotating cylinder and the remainder being composed of a stationary cylinder, means for sealing the opening between said rotating cylinder and said stationary cylinder.
- 25 9. In a refrigeration system, a drum, means for
- 5 rotating said drum, said drum having a compressor near its center and having fins spaced between said compressor and the periphery of said drum, a passageway connecting said drum to a vaporizer or cooling element, a portion of said passageway being composed of a rotating cylinder and the remainder being composed of a stationary cylinder, means for sealing the opening between said rotating cylinder and said stationary cylinder, means for removing said rotating cylinder without disturbing said sealing means.
- 10 10. In a refrigeration system, a drum, means for rotating said drum, said drum having a compressor near its center and having fins spaced between said compressor and the periphery of said drum, a tube or passageway leading from said drum, said tube having a circular member dipping into an annular cup containing liquid, said annular cup being connected to a tube leading to a vaporizer, said tube forming a sealed passageway connecting said compressor and said vaporizer.
- 15 11. In a refrigeration system having a rotating unit, comprising a compressor and condenser and a stationary unit, comprising a vaporizer or cooling unit, said rotating unit being encased, said encasement having means for admitting external air for cooling said rotating unit.
- 20 12. In a refrigeration system having a rotating unit, comprising a compressor and condenser, and a stationary vaporizer or cooling unit, said rotating unit communicating with said stationary vaporizer or cooling element, said rotating unit having means on its outer side for air circulation.
- 25 35

KEMPER MARTEL HAMMELL.
